UNITED STATES PATENT OFFICE

JOHN WARREN VEDDER, OF WORCESTER, MASSACHUSETTS

PAPER-MAKING MACHINE

Application filed June 28, 1926. Serial No. 119,151.

This invention relates to paper making machines and more particularly to the deckles employed therewith for preventing the stock in its liquid state from running off the edges of the Fourdrinier wire.

In Fourdrinier paper making machines the deckles have heretofore generally consisted of endless straps passing around pulleys, the lower part of the strap in extending from one pulley to the other also resting on and along the wire so as to be propelled by and travel with the wire. It has been the practice to run these deckles along the wire, to a point past the first, or in some cases past the second, suction box; and then to return them. This stretch of wire from the slice to the first or second suction box is known as the forming surface of the wire; and thus it correctly states what has been the common practice heretofore to say that the deckle straps extend from the breast-roll a distance equal to at least that of the so-called forming surface of the wire.

I have discovered, however, that the length of contact of the deckle straps with the wire may be shortened to a very material extent; the fact being, as I have discovered, that the web or sheet of paper stock forms an edge sufficiently coherent or self-retentive to permit dispensing with deckles, when the web has travelled a distance considerably less than the length of the so-called forming surface of the wire. It follows that the length of the deckle straps may be very materially reduced with no detriment to the web of paper in process of formation, and, on the other hand, with important advantages in the saving of cost of construction and operation. In other words, according to the present invention, the distance which the deckle straps extend along the wire is considerably shortened, preferably to the extent attained by terminating the engagement of the straps with the wire approximately at the point where the web or sheet has reached such stage of formation that its edges will hold. This point of terminating the deckle may vary somewhat with conditions, such as the particular characteristics of the paper stock being employed, but in any event the length.

of the deckle heretofore considerably less than that of deckles heretofore commonly used, while at the same time being of sufficient length to keep the stock from flowing off the edges of the wire prior to formation of the web. What this means practically is that, by means of the present invention, the length of contact between the deckle straps and the wire may be reduced to a half, or a third, and in some cases to even a quarter, of what is now common in mill practice.

I have also discovered that deckle straps, although resting upon and being supported by the wire, need not travel forward with the wire, but on the contrary may be fixed against such participation in the forward movement or travel of the wire. Therefore, according to the present invention, it is proposed to anchor or fix the deckle straps against forward movement with the wire, and furthermore to dispense with the continuous double reach or double length deckles running from one pulley to another and to employ instead what may be termed single reach or single length deckle straps each extending along and resting upon and being supported by the wire and preferably anchored at its end nearest the slice.

As thus appears, in contrast to deckle straps heretofore commonly used, some of the advantages and objects attained by the present invention are the provision of deckle straps which are shorter in the length thereof in engagement with the Fourdrinier wire; which are single reach straps instead of double reach continuous straps such as used with pulleys; which require less material and hence are much lighter and cheaper; which require fewer mechanical parts in the making and installing of deckle equipment; and which can be fixed against traveling movement with the Fourdrinier wire while at the same time being supported on and by the traveling wire without excessive friction, this being made possible largely by the reduced length and weight of the deckle straps. Other objects attained are reduction in mass and weight of deckle strap equipment to be vibrated with the wire by the shake motion; and the possibility of applying deckle straps of this in-

vention to existing equipment, thereby avoiding the losses ordinarily incident to the replacement of an old with a new type of mechanism or device.

5 The aforesaid and still other objects and advantages hereinafter explained or apparent from the detailed description and drawings are attained by this invention and by the now preferred mechanical embodiment thereof illustrated in the accompanying drawings, wherein—

10 Fig. 1 is a perspective view of part of a Fourdrinier paper-making machine equipped with deckle straps in accordance with the present invention;

15 Fig. 2 is an enlarged detail perspective view;

20 Fig. 3 is a transverse sectional view on line 3—3 of Fig. 1 and showing mechanism for adjusting the deckles, deckle frames, and pond walls laterally of the machine;

25 Fig. 4 is a side view showing particularly said adjusting means shown in Fig. 3;

30 Fig. 5 is a sectional view longitudinally of the Fourdrinier wire, and Fig. 6 is a front view showing another embodiment of the invention;

35 Fig. 7 is a sectional view longitudinally of the Fourdrinier wire, and Fig. 8 is a top plan view, showing other means for anchoring or securing a deckle strap in accordance with the present invention;

40 Fig. 9 is a sectional view longitudinally of the Fourdrinier wire showing another embodiment of means for anchoring or securing a deckle strap in accordance with the present invention;

45 Fig. 10 is a top plan view, and Fig. 11 is a front view, showing another embodiment of the invention;

50 Fig. 12 is a top plan view, and Fig. 13 is a sectional view longitudinally of the Fourdrinier wire, showing still another embodiment of the invention;

55 Fig. 14 is a perspective view and Fig. 15 is a sectional view of still another embodiment of the invention.

60 Referring first to the embodiment of the invention shown in Figs. 1 to 4, 5 is the Fourdrinier wire passing over table rolls 6, 6, around breast roll 7, and under stretch roll 8, at the wet end of the machine. The table rolls and breast roll are journaled in any suitable manner on a spring-supported shake frame which includes the yoke 9 and the shake rails 10, 10 pivotally connected to said yoke at 11, 11. The shake frame is vibrated laterally of the machine by a shake motion (not shown) which is connected to said frame at 12 by a connecting rod 13, as shown in Fig. 3. A flow-box 14 has secured to the front wall thereof an apron-board 15 having attached thereto a flexible apron 16 which projects over the Fourdrinier wire 5 at the breast roll 7 and is slightly spaced from the wire. A

65 pair of pond plates 17, 17 are positioned against the front wall of the flow-box 14 at opposite ends thereof, respectively, each plate being adjustably secured in place by a wing bolt 19 passing through a slot 21 of the plate. 70 A bracket 18 is secured to each pond plate 17, and said bracket is adjustably secured to the apron-board 15 by means of a wing bolt 20 passing through a slot 22 of said bracket 18. 75 A pond wall 23 is adjustably secured to each bracket 18 by two wing bolts 24, 24 passing through slots 25', 25' of the bracket. At their outer ends the pond walls 23, 23 are connected to deckle frames 25, 25 respectively, as by bolts 26, 26, which bolts also serve to 80 secure bracket arms 27, 27 to the deckle frames. On each of the arms 27, 27 there is a stud shaft 28 (Fig. 2) which carries a pulley or wheel 29 such as ordinarily heretofore used with continuous deckle straps. The slice 85 under the lower edge of which the stock flows onto the wire is formed of two plates or sections 41, 41, the outer ends of which fit against the inner surfaces of the pond walls 23, 23, respectively, said plates at their inner ends overlapping each other and being adjustably 90 secured together by wing bolts 42, 42 on one plate passing through slots 43, 43 of the other plate. The lower edge of the slice, that is the lower edges of plates 41, under which the liquid stock is delivered, curves forwardly and outwardly, said edges being flexible and thereby adjustable to deliver thereunder the desired uniform thickness of flow of stock. 95 Each pond wall 23 has on its inner face a 100 bracket 44. A strut bar formed of two telescoping sections 45, 45 is secured at its opposite flattened ends 46, 46 to said brackets 44, 44 by set screws 47, 47 threaded through arms 48, 48 of the brackets 44, 44 respectively, said set screws passing through said flattened ends of the strut bar. Each set screw 47 has two lock nuts 49, 49 positioned respectively above and below the flattened end 46 of the 105 strut bar, thereby securing the latter in any desired position of vertical adjustment on the set screw. The sections or plates 41, 41 of the slice are made of flexible metal or other suitable material to provide for warping or bending of their lower edges 50, 50 thereby to deliver onto the wire 5 a flow of stock of the desired uniform thickness corresponding to the entire width of the web of paper to be produced. Warping or bending of said lower edges 50, 50 of the slice sections is effected by 110 means such as the series of bolts 51, each pivotally connected at its lower end at 52 to a plate 53 secured to the extreme lower edge 50 of the slice. Each bolt 51 has a threaded upper end which passes loosely through a 115 suitable opening in the strut bar and is engaged by a nut 54, the turning of which will raise or lower its bolt 51. A lock nut 55 on each bolt 51 below the strut bar 45 secures the 120 bolt in position to which it is adjusted to pro- 125

duce the desired warping of the lower edge of the slice. Brace arms 56, Fig. 1, are secured at one end to the outer face of sections or plates 41, 41 of the slice; at their outer ends said arms 56 have openings through which the bolts 51 pass respectively.

The deckle frames 25, 25, pond walls 23, 23, pond plates 17, 17, and the slice composed of plates 41, 41, are all adjustable transversely 10 of the machine according to the particular width of web or sheet which it is desired to produce. In providing such adjustment, each deckle frame has secured thereto two sleeves 32, 32 slidably mounted on tubular 15 bars 33, 33, respectively, said bars extending transversely of the machine through openings in the deckle frames and at their opposite ends being supported by pillars 34, 34 mounted on longitudinal sill pieces 35, 35 of 20 the machine base. A pair of shafts 36, 36 extend into the opposite ends respectively of the tubular bars 33, 33, the inner screw-threaded ends of said shafts engaging threaded openings respectively of a pair of 25 blocks 36', 36' positioned within said tubular bar. The lower end 36'' of each block 36' extends through an elongated slot on the under side of its tubular bar 33 and is rigidly secured to the corresponding sleeve 32, 30 thereby providing for inward and outward movement or adjustment of said sleeves, and of the deckle frames to which they are secured, by rotation of the shafts 36. A bevel gear 37 fixed to each shaft 36 meshes with a 35 bevel gear 38. The two bevel gears 38, 38 at one side of the machine are fixed to a shaft 39, and the two bevel gears 38, 38 at the other side of the machine are similarly fixed to another shaft 39. Rotation of one shaft 36 at 40 one side of the machine by a crank handle 40 thereon imparts like rotation to the other shaft 36 at that side of the machine through the bevel gears 37, 38, and shaft 39. A similar crank handle 40 on one of the shafts 36 45 at the other side of the machine serves in like manner to rotate both shafts 36 together. By such means the parts can be adjusted from or toward each other according to whether it is desired to increase or decrease the width of 50 the paper web to be produced.

The parts of the mechanism thus far set forth in the detail description being generally of construction well known in the practical art, further description thereof herein is unnecessary.

As well known, deckle straps as heretofore commonly employed consist each of a continuous band or strap of rubber material extending over pulleys at opposite ends thereof, the lower side of the continuous strap between the two pulleys extending from the slice along and in engagement with the Fourdrinier wire to a point beyond the first and frequently beyond the second suction box. By such engagement of strap and wire, the longitudinal

or forward movement of the wire is transmitted to the deckle strap and the pulleys rotate as the strap travels with the wire. In the embodiment of the present invention shown in Figs. 1 to 4, two deckle straps are 70 shown at 30, 30. Each strap may be made of the usual rubber material and of the usual dimensions in cross-section. But instead of the usual continuous double length strap, each deckle strap 30 is of single length or reach, 75 rests upon, is supported by, and extends along the wire, but is fixed or anchored against participation in the longitudinal movement of the wire. Furthermore, instead of extending along the wire a distance approximately equal to what has heretofore been known as the forming surface, that is, to the first or second suction box, each deckle strap 30 of this invention is much shorter, being 80 terminated at approximately the distance 85 from the slice at which the edges of the web or sheet will have sufficiently formed so that the stock will not run off the edges of the wire, or in other words, will have formed sufficiently not to require thereafter the presence 90 of deckle straps. That is to say, according to this invention, the deckle straps, whether of the single or the double reach type, instead of extending from the breast roll to a point 95 beyond the first or the second suction box (as those boxes are ordinarily placed in a Fourdrinier machine) extend only to a point that is a substantial distance short of the first suction box. Such shortening of the length of 100 engagement of the strap with the wire, as well as the use of a single reach or single length strap in contrast to the usual continuous double reach and hence double length strap, not only effects a considerable saving in 105 quantity of material used in producing the straps, but also materially reduces bulk and weight of the straps to such an extent as to enable the wire to support the straps entirely 110 without undue strain upon the wire or frictional resistance to its forward movement.

As shown in Figures 1 to 3, the machine has the usual equipment of pulleys such as 29 for endless deckle straps such as heretofore used. The deckle strap 30 at one end extends partly around pulley 29 with said end secured to the pulley by a clamp 57 engaged over the strap and the felly of the pulley and held in position by a set-screw 58 and lock-nut 58'. The pulley 29 is shown as being held against rotation by a set-screw 59 threaded through hub 60 of the pulley into engagement with the stud shaft 28. A pin 61 on bracket 27 is also shown as standing in the path of one of the spokes 62 of the pulley, thus serving as 115 a further means for preventing rotation of the pulley and anchoring the strap 30 at one end to prevent it from participating in the forward movement or travel of the wire. From its point of anchorage to its pulley, 120 each deckle strap extends along the surface 125 130

of the wire approximately under its corresponding deckle frame 25. The weight of the straps and their engagement with the traveling wire will maintain them in approximate parallelism with each other from end to end. Adjustments of the deckle frames 25 and other parts for narrower or wider webs of paper will be communicated to the deckle straps.

In the embodiment of the invention shown in Figs. 5 and 6, the adjustable pond walls, deckle frames, and parts connected therewith, are dispensed with, the flow-box 14 being provided with rigid pond walls one of which is indicated at 63. The slice in this instance comprises a single plate 64 which extends across the entire width of the pond and is mounted on said rigid pond walls. The plate 64 has riveted or otherwise suitably secured to the lower edge thereof a relatively wide intermediate flexible slice element 65 arcuate-shaped in cross section, and a plurality of narrower flexible slice elements 66, 66 of like configuration disposed in end to end abutting relation at both ends of the intermediate flexible slice element 65. Short single reach deckle straps 67 are employed, and are supported on the wire 5. Each strap has a reduced end portion 68 which may be clamped between any one of the flexible slice sections and the flexible apron 16 by means of the proper bolt 51 and its adjusting nuts 54 and 55 in cooperation with strut bar 45'. As shown in Figs. 5 and 6, the end 68 of the deckle is clamped under one of the narrower flexible slice elements 66, the others of which bear on the apron 16 so as to form a dam and prevent the stock from flowing past any portion of the slice extending outwardly from the deckle 67. The stock thus flows under the slice element 65 and is confined on the wire by the deckles. With this arrangement, the deckles may be adjusted laterally of the machine by hand in order to obtain a web in sheet of the desired width, the end 68 of the deckle being clamped between the flexible apron 16 and the flexible slice element which is located in line with the deckle after its adjustment. When the desired adjustment of the deckles has been obtained, the flexible slice element or elements disposed outwardly of the deckles are depressed into engagement with the apron while those disposed between the deckles are lifted to provide the required opening for the flow of stock onto the wire. The end 68 of each deckle is preferably held in engagement with the rear curved surface of the slice by a clip 68' riveted or otherwise suitably secured to the slice. Warping or curving of the lower edge of the slice may be effected as before described, to provide a flow of stock which is uniform in thickness across the entire width of the web to be formed.

Instead of employing deckles with straight

ends, such as shown in Figs. 1 to 6, deckles with L-shaped ends may be employed as illustrated in Figs. 7 and 9 to 11. In such use of deckles with L-shaped ends, additional clamping devices are preferably provided for securing the ends of the deckles between the flexible apron 16 and flexible slice. As shown in Figs. 7 and 8, each additional clamping device comprises a bail 69 mounted on one of the plates 53. For this purpose the clip is provided at the rear thereof with apertured bosses 70, 70 in which are journaled the free ends 71, 71 of the bail, and the sides 72, 72 of the bail are normally engaged under lugs 73, 73 on the sides of the plate. The front of said bail is formed with spaced yokes 74, 74 and an intermediate yoke 75, the yokes 74, 74 engaging across the edge of the L-shaped end of the deckle, and the yoke 75 constituting a finger pull for disengaging the bail from the deckle and lugs 73, 73.

In the embodiment shown in Fig. 9, the plate 53 is secured to the lower edge of the flexible slice by a rivet 76 provided with a conical head which embeds itself in the L-shaped end of the deckle when the edge of the flexible slice is depressed by the bolt 51.

In the embodiment of the invention shown in Figs. 10 and 11, the short single reach deckle strap 78 has an L-shaped end providing a pull strap 79 which serves as means for manually adjusting the deckle laterally of the machine. When the desired adjustment of the deckles has been obtained, the strap 79 of each deckle is clamped between the flexible apron 16 and the lower edge of a single-piece flexible slice 80, thus preventing movement of the deckle with the wire 5 and preventing the stock from flowing beneath any portion of the slice outside of the deckles.

As shown in Figs. 12 and 13, the short single reach deckle strap 81 has secured to the angular portion 82 of its L-shaped ends a block 83 of wood or other suitable material. The portion 82 of the deckle is secured to the front edge of the block by a screw 84 and the surface of the block rearwardly of the slice 85 is curved to fit the latter. The block 83 serves as means for manually adjusting the deckle laterally of the machine and, after the desired adjustment has been made, the block of each deckle acts as a dam to prevent the stock from flowing beneath any portion of the slice outside of the deckles. At the same time the deckle 81 supported on the wire 5 is prevented from moving with the latter by the block 83.

In the embodiment shown in Figs. 14 and 15, an angular re-enforcing bar 86 is secured in any suitable manner to the lower edge of a single-piece flexible slice 87. On each end of the bar 86 is secured an angle bar 88, the connection for which with the bar 86 is provided by wing bolts 89, 89 on bar 86 passing through slots 90, 90, in the bar 88. The

deckles 91, 91 are comprised by single reach straps supported on the wire 5 and at one end secured, respectively, to the inner ends of the angle bars 88, 88 by brackets 92, 92. Through the medium of the wing bolts 89, 89 and slots 90, 90, the deckles 91, 91 may be adjusted manually toward and from each other to produce a web of any desired width, the angle bars 88, 88 preventing the flow of stock beneath any portion of the slice outside of the deckles 91, 91 and, together with the brackets 92, 92, serving to anchor the deckles against movement with the wire 5.

What is claimed is:—

15. 1. In a Fourdrinier paper-making machine, the combination with the endless wire, of single reach deckle straps supported by the wire and extending along the same for a portion only of the length of the forming surface of the wire, and means for adjusting said deckle straps laterally of the machine.
20. 2. In a Fourdrinier paper-making machine, the combination with the endless wire on which the web is formed and means for imparting longitudinal movement to said wire, of a deckle extending along and in engagement with and supported by said wire and secured against movement with the wire in said longitudinal movement of the wire.
25. 3. In a paper-making machine, the combination of a longitudinally movable part on which the web is formed, and deckling means supported by said movable part and secured against movement longitudinally therewith.
30. 4. In a paper-making machine, the combination of a longitudinally movable part on which the web is formed, deckling means supported by said part and secured against movement longitudinally therewith, and means for adjusting said deckling means laterally of the machine.
35. 5. In a paper-making machine, the combination of a longitudinally movable part on which the web is formed, a pair of spaced deckles supported by said part and secured against movement longitudinally therewith, and means for adjusting said deckles laterally of the machine.
40. 6. In a Fourdrinier paper-making machine, the combination with the longitudinally movable endless wire, of deckling means supported by said wire and secured against movement longitudinally therewith, and means for adjusting said deckling means laterally of said wire.
45. 7. In a Fourdrinier paper-making machine, the combination with the longitudinally moving endless wire, of a deckle supported on said wire, and means for attaching said deckle to a part of the machine so as to prevent movement of the deckle longitudinally with said wire.
50. 8. In a paper-making machine, the combination of a movable wire part on which the web or sheet is formed, means for regulating

the flow of stock thereon, and deckling means supported by said wire part and anchored to said regulating means.

9. In a paper-making machine, the combination of a movable endless wire part on which the web or sheet is formed, means for delivering the stock thereon including a slice, and deckling means supported by the endless wire part and anchored to said slice. 70

10. In a Fourdrinier paper-making machine, the combination of a flexible slice for controlling the flow of stock from the flow-box onto the endless wire, and a deckle having one end thereof anchored by being secured between the flow-box apron and a portion of said slice. 75

11. In a Fourdrinier paper-making machine, the combination of a slice provided with one or more displaceable lower edge portions, and a deckle extending along the endless wire and at one end secured between the apron-board and one of said displaceable lower edge portions. 80

12. In a paper-making machine, the combination of a movable part on which the web is formed, a slice for regulating the flow of stock onto said movable part and having a flexible lower edge portion, and a deckle extending along the part and secured between said flexible edge portion of the slice and a stationary part of the machine. 85

13. In a paper-making machine, the combination of a movable part on which the web is formed, a slice, means for adjusting the slice to regulate the flow of stock onto said movable part, and a deckle strap extending along the movable part and having one end secured between the lower edge portion of said slice and a stationary part of the machine. 90

14. In a paper-making machine, the combination of a movable web-forming part, a slice for regulating the flow of stock onto said part, deckling means extending over the movable web-forming part and secured between the lower edge of the slice and a stationary part of the machine, means for adjusting the slice and deckling means to vary the width of the web, and means for preventing the flow of stock below any portion of the slice outside of said deckling means. 95

15. In a paper-making machine, the combination of a movable web-forming part, a slice for regulating the flow of stock onto said part, deckling means extending along the movable web-forming part, means for adjusting the deckling means to vary the width of the web, and means for preventing the flow of stock below the slice outside of the deckling means. 100

16. In a paper-making machine, the combination of a movable web-forming part, a slice for regulating the flow of stock onto said part, deckling means extending along the movable web-forming part, means for ad- 105

justing the deckling means to vary the width of the web, and means secured between the lower edge of the slice and a stationary part of the machine for preventing the flow of stock below the slice outside of the deckling means.

17. In a Fourdrinier paper-making machine, the combination with the endless longitudinally movable wire, of a single reach 5 deckle extending along upon and supported by the wire.

18. In a Fourdrinier paper-making machine, the combination with the endless longitudinally movable wire, of a pair of spaced 10 single reach deckles extending along upon and supported by the wire.

19. A deckle consisting of a single reach 15 of flexible material adapted to be supported on the web-forming part of a paper-making machine.

20. A deckle consisting of a single reach of material adapted to be supported on the web-forming part of a paper-making machine and being flexible to conform to the 20 surface of said part.

21. In a Fourdrinier paper-making machine, the combination with the endless wire, of deckling means supported by the wire and extending along the same for a portion only 30 of the length of the forming surface of the wire, and means securing the deckling means against movement longitudinally with said wire.

22. In a Fourdrinier paper-making machine, the combination with the endless wire on which the web is formed, of a deckle extending along and in engagement with said endless wire only to the approximate point thereon of formation of the web, said deckle 40 being secured against movement with the wire in said longitudinal movement of the wire.

23. In a Fourdrinier paper-making machine, the combination with the endless wire, of a single reach deckle strap supported by 45 said wire and having a length less than that of the forming surface of the wire.

24. In a Fourdrinier paper-making machine, the combination with the endless wire on which the web is formed, of a single reach 50 deckle extending along and in engagement with the wire only to the approximate point thereon of formation of the web.

25. In a Fourdrinier paper-making machine, the combination of a single reach 55 deckle strap extending along and supported upon the endless wire and of a length less than that of the forming surface of said wire, and means for anchoring said deckle to a stationary part of the machine.

26. In a Fourdrinier paper-making machine, the combination with the endless wire on which the web is formed, of a single reach 60 deckle extending along and in engagement with the wire only to the approximate point 65 thereon of formation of the web, said deckle

being secured against movement with the wire in said longitudinal movement thereof.

27. In a Fourdrinier paper-making machine, the combination with the endless longitudinally movable wire, of a single reach 70 deckle extending along upon and supported by the wire, said deckle being anchored against movement with the wire in the longitudinal movement of the latter.

28. In a Fourdrinier paper-making machine, the combination with the moving endless wire, of a deckle comprising a single reach 75 of material supported by the moving wire and anchored to a stationary part of the machine.

29. In a paper-making machine, the combination of a movable web-forming part, a single reach deckle strap supported by said movable part, and means anchoring the strap to a normally stationary part of the machine 80 so as to prevent movement of said strap longitudinally with the web-forming part.

30. In a paper-making machine, the combination of a movable part on which the web is formed, a single reach deckle strap supported by said part and anchored against movement longitudinally therewith, and means for adjusting said deckle strap laterally of the machine.

31. In a Fourdrinier paper-making machine, the combination with the movable wire part, of a single reach deckle strap supported on the movable wire part and provided with means attachable to a part of the machine to prevent movement of the strap 95 longitudinally with said wire part.

32. In a paper-making machine, the combination of a movable part on which the web or sheet is formed, means for delivering the stock thereon, and a deckle supported by said 100 movable part and anchored against movement longitudinally therewith by said stock delivering means.

33. In a paper-making machine, the combination with the moving endless wire, of a 110 slice for regulating the flow of stock onto said wire, a single reach deckle extending over said wire and having one end secured between the lower edge of the slice and another part of the machine, means for adjusting the 115 deckle laterally of the machine, and means for preventing the flow of stock below the slice outside of said deckle.

34. In a paper-making machine, the combination of a movable web-forming wire, a 120 slice for regulating the flow of stock onto said wire, a single reach deckle extending over the wire and having one end secured between the lower edge of the slice and another part of the machine, means for adjusting the deckle 125 laterally of the machine, and means for preventing the flow of stock below the slice outside of said deckle.

35. A deckle comprising a single reach of material adapted to rest upon and be sup- 130

ported by the web-forming part of a paper-making machine and being provided adjacent one end with means for attachment with a stationary part of said machine.

5 36. A deckle comprising a single reach of material adapted to be supported on the web-forming part of a paper-making machine, said deckle having a substantially L-shaped end constituting means for anchoring the deckle to a part of the machine and for adjusting the deckle laterally thereof.

10 In testimony whereof I have signed this specification.

JOHN WARREN VEDDER.
